ANNA BAKER, OF BALTIMORE, MARYLAND, ASSIGNOR OF ONE-HALF TO EDVA BAKER,
OF BALTIMORE, MARYLAND.

BODKIN.

1,390,864.

Specification of Letters Patent. Patented Sept. 13, 1921.

Application filed February 26, 1921. Serial No. 448,211.

To all whom it may concern:

Be it known that I, ANNA BAKER, a citizen of the United States, residing at Baltimore, in the county of Baltimore City, and 5 State of Maryland, have invented new and useful Improvements in Bodkins, of which the following is a specification.

The object of my present invention is the provision of a bodkin constructed in 10 a simple, inexpensive and durable manner and with a view to being readily threaded, and one that is adapted to be used to advantage in carrying a cord, ribbon or the like through the hems or eyelets or other 15 openings in wearing apparel, particularly the wearing apparel of women.

To the attainment of the foregoing, the invention consists in the improvement as hereinafter described and definitely claimed.

20 In the accompanying drawings, forming part thereof:—

Figure 1 is a side elevation showing my novel bodkin as open and ready to be expeditiously and easily threaded.

25 Fig. 2 is an elevation of the opposite side of the bodkin as it appears when closed subsequently to the threading operation.

Figs. 3 and 4 are views of the edges of the bodkin.

30 Fig. 5 is an enlarged transverse section taken in the plane indicated by the line 5—5 of Fig. 2.

Similar numerals of reference designate 35 corresponding parts in all of the views of the drawings.

In the present and preferred embodiment of my invention the bodkin is formed in one piece of metal appropriate to its purpose, and among other elements it comprises a 40 substantially straight body bar 1. At one end the said bar 1 is merged into the bight of a loop 2, and the outer arm 3 of the said loop is provided with a tapered or pointed free end 4. It will also be observed that the 45 said tapered or pointed end portion 4 is slightly deflected in a direction away from the body bar 1. At its opposite end the body bar 1 is merged into the bight of a permanently closed loop 5. The outer arm 6 of the 50 said loop 5 is inclined inwardly, and at a point adjacent to the transverse center of the body bar 1 is merged into a transverse loop 7 that straddles and receives the body bar

1. The bight 8 of the said loop 7 rests against one edge of the body bar 1, and at 55 the free end of said loop 7 is provided a lateral extension 9 that constitutes a keeper for the free end 4 of the arm 3; the said keeper being spaced as illustrated from the adjacent edge of the body bar 1. 60

My novel bodkin is threaded with a ribbon, cord or the like while the arm 3 is open as appears in Fig. 1, after which the free end portion of the loop 2 is snapped into engagement with the keeper 9 when as will 65 be readily observed the said end 4 will be held against casual release and the point will be guarded and prevented from the interfering with the passage of the bodkin through material. It will be noted in this 70 connection that it is entirely within the purview of my invention to impale the ribbon, cord or the like on the arm 3 so that the threading of the bodkin will involve 75 positive connection of the ribbon or cord to the bodkin with the result that accidental release of the ribbon or cord while the bodkin is in use will be precluded. In addition to the practical advantages hereinbefore ascribed to my novel bodkin, it will 80 be manifest that the bodkin is susceptible of being inexpensively and easily produced without the employment of complicated machinery, and that the bodkin embodies no delicate parts such as are likely to get out 85 of order after a short period of use.

Having described my invention, what I claim and desire to secure by Letters-Patent, is:—

As a new article of manufacture, a bodkin, 90 formed in one piece of metal and consisting essentially of a straight body bar, a loop at one end of the body bar and having an outer arm the free end of which is pointed and is deflected slightly away from the body 95 bar, a loop at the opposite end of the bar and having an outer arm inclined inwardly and provided at its inner end with a transverse loop straddling the body bar adjacent to the transverse center thereof, and a 100 keeper for the pointed end of the first-named arm, carried by the transverse loop and spaced from the adjacent edge of the body bar.

In testimony whereof I affix my signature. 105
ANNA BAKER.
